UNITED STATES PATENT OFFICE.

THOMAS MARTIN, OF VANCOUVER, BRITISH COLUMBIA, CANADA.

SAFETY DEVICE FOR ELECTRIC IRONS.

1,372,361.

Specification of Letters Patent. Patented Mar. 22, 1921.

Application filed May 13, 1920. Serial No. 381,118.

To all whom it may concern:

Be it known that I, THOMAS MARTIN, a subject of the King of Great Britain, and a resident of the city of Vancouver, in the Province of British Columbia, Canada, have invented certain new and useful Improvements in Safety Devices for Electric Irons, of which the following is a specification.

My invention relates to improvements in safety devices for electrically heated irons, and the object of my invention is to provide a simple means for preventing overheating of an iron should the same be left unattended for any length of time with the current still turned on, thus eliminating entirely all danger of fire from this source. A further object is to devise such a means which is removable and replaceable with great convenience and facility.

I attain these objects by the construction illustrated in the accompanying drawings in which—

Figure 1 is an elevation of an iron fitted with my device.

Fig. 2 is a sectional view taken on the line 2—2 of Fig. 1.

Fig. 3 is an outside view of the plug.

Fig. 4 is a view of the plug, in part section.

Similar figures of reference indicate similar parts throughout the several views.

1 indicates a typical electric iron, provided with a heating block 2 to which are connected the wires 3 and 4 of the electrical circuit. The terminal 5 of the wire 4 is broken to provide a gap 6, which gap is bridged by a tip 7, of lead or other material which is fusible when the temperature reaches the danger point, and this tip is pro-

vided with a reduced shank portion 7' which 40 is removably inserted in a bushing 8 of fiber or other insulating material placed in the bore 9 of a plug 10 threaded at its outer end as at 11. 12 indicates a boss formed on the inside of the cover 13 of the iron having a 45 threaded bore 14 corresponding to the threaded portion 11 of the plug. The outer end of the plug is provided with a screw driver slot 15.

In use the plug is screwed into the bore 14 50 until the fusible tip 7 bears on the divided ends of the terminal 5 to bridge the same and complete the electrical circuit. When the iron becomes heated to a temperature liable to set on fire the stand on which it is 55 resting the tip 7 melts, so that the circuit is broken, and thus the danger is automatically prevented. To restore the iron to its effective condition again all that is necessary is to take a screw driver and unscrew the 60 plug, insert a new tip in the fiber bushing and replace the plug, from which it will be seen that the object sought to be attained is effected in the most simple, convenient, and inexpensive manner. 65

What I claim as my invention is:

A fuse plug comprising a plug body provided at its inner end with a hollow sleeve, a solid body of insulating material filling the interior of said sleeve and projecting beyond the free end thereof, and a fusible contact tip provided with a reduced shank portion embedded in the projecting portion of said insulating material. 70

Signed at Vancouver, B. C., Canada, this 75 4th day of May, 1920.

THOMAS MARTIN.
